UNITED STATES PATENT OFFICE.

WILLIAM WHITNEY TODD, OF CHICAGO, ILLINOIS.

MOP-WRINGER.

No. 852,043.

Specification of Letters Patent.

Patented April 30, 1907.

Application filed February 16, 1903. Serial No. 143,744.

To all whom it may concern:

Be it known that I, WILLIAM WHITNEY TODD, a subject of His Majesty the King of Great Britain, residing at Chicago, in the county of Cook and State of Illinois, have invented a new and useful Improvement in Mop-Wringers, of which the following is a specification.

My invention relates to certain improved details of construction of an apparatus for wringing mops, which will be first described with reference to the accompanying drawings and specifically pointed out in the claim.

The drawing is a view in perspective of my said improved device.

The base of my said new mop-wringer is made of bar-steel bent sidewise so as to form an end piece *n* bent at the corners *a* to form the sides *b* which are then bent edgewise at *s* to form arms *c* which overhang the base *b* so that the relative directions of the parts *b c* form an acute angle between them, substantially as shown. Between the free ends of the arms *c* is held a wringer roller *r*, and with *t* said base is complete.

At a suitable height from the curves *s* are holes *d* and pivoted therein is a piece of mechanism, similar to that just described, of which

the sides and arms are shorter and the angle 30 between the sides and arms less acute, but the parts are wide enough apart to pass over the outside of the arms *c* it being formed of the straight end-piece *k* from which the parallel sides *e* project and on the latter, bent 35 edgewise at *f*, are the arms *t* which carry a wringer-roller *o* in their outer ends, which is provided with a crank *h*. Said second element is pivoted at its bend *f* to the arms *c*, at *d*, on pins *v* upon which it vibrates, and the 40 rollers *r o* are kept apart by means of a suitable spring *x*. When the cross-bar *k* is depressed the rollers *o r* are brought into contact and they are separated by the action of the spring *x*.

What I claim is:

The combination with a three-sided base provided with upturned arms set at an acute angle to the base, and a roller in the ends of said arms, of a vibratable element pivoted to 50 the arms of said base consisting of an end-piece and side-pieces bent edgewise into upturned arms provided with a roller, and means to operate said roller.

WILLIAM WHITNEY TODD.
